United States Patent Office

Des. 192,623
Patented Apr. 17, 1962

192,623

DISPLAY STAND FOR PACKAGED GOODS

Willy J. A. De Nys, 1470 E. Valley Road, P.O. Box 5101,
Santa Barbara, Calif.

Filed Aug. 22, 1961, Ser. No. 66,458

Term of patent 3½ years

(Cl. D80—9)

FIG-2

FIG-3

FIG-4

FIGURE 1 is a perspective view of a display stand for packaged foods, showing my new design;

FIGURE 2 is a side elevational view thereof;

FIGURE 3 is a front elevational view thereof; and

FIGURE 4 is a top plan view thereof.

The rear of this display stand is substantially plain.

I claim:

The ornamental design for a display stand for packaged foods, as shown and described.

References Cited in the file of this patent

UNITED STATES PATENTS

D. 91,826	Jackson	Mar. 27, 1934
D. 95,328	Ginsburg	Apr. 23, 1935
D. 173,627	Nichols	Dec. 7, 1954
1,955,370	Snook et al.	Apr. 17, 1934